UNITED STATES PATENT OFFICE.

FRED B. WILLIAMS, OF MONROE, MICHIGAN, ASSIGNOR TO THE ELKHART MANUFACTURING COMPANY, OF MONROE, MICHIGAN, A CORPORATION OF MICHIGAN.

IGNITION APPARATUS FOR EXPLOSION-ENGINES.

1,158,762.

Specification of Letters Patent.

Patented Nov. 2, 1915.

Application filed May 2, 1913. Serial No. 765,046.

To all whom it may concern:

Be it known that I, FRED B. WILLIAMS, a citizen of the United States of America, residing at Monroe, in the county of Monroe and State of Michigan, have invented certain new and useful Improvements in Ignition Apparatus for Explosion-Engines, of which the following is a specification, reference being had therein to the accompanying drawings.

The invention relates to electric ignition systems of that type in which the generator for the current is mechanically driven from the engine.

15 It is the primary object of the invention to provide means for producing an efficient spark when the speed of the engine is too low for the efficient operation of the generator.

20 It is a further object to provide means for automatically retarding and advancing the spark corresponding to changes in speed of the engine.

With these objects in view, the invention 25 comprises a magneto or other electric generator mechanically actuated, together with means for driving said generator either synchronously or non-synchronously with the engine.

30 The invention further comprises means for retarding and accelerating the speed of the generator relative to that of the engine in different portions of the same cycle when the engine is running at low speed, and for 35 automatically changing to a synchronous movement throughout the cycle when running at normal speed.

Still further, the invention comprises various features of construction as hereinafter 40 set forth.

In the drawings: Figure 1 is an elevation of a magneto generator showing in section the driving shaft and automatic accelerating and retarding mechanism; Fig. 2 is a cross 45 section on line *x*—*x* Fig. 1; and Fig. 3 is a view similar to Fig. 1, showing a slightly modified construction; and Fig. 4 is a cross section on line *y*—*y* Fig. 1.

A is the mechanically-actuated generator—such as a magneto, of any suitable construction, and B is the drive shaft therefore, receiving its power from the engine (not shown). It is usual to couple the magneto and its drive shaft so as to maintain 55 a constant speed ratio and fixed timing, but

with such constructions the generator does not become efficient until the normal engine speed is attained. Thus, in starting, the current generated is not sufficient to operate the igniters. With my improved construction, I overcome this defect by providing means for accelerating the speed of the generator during a portion of its cycle, including the time of sparking, and in compensating for this acceleration by the arresting 60 or retarding of the generator during another portion of the cycle. I further provide automatic governing means, by which this non-synchronous movement of the generator is changed into a synchronous movement 65 when the engine has attained its normal running speed.

Various specific constructions may be employed for accomplishing the movements as above set forth, but, as shown, the construction is as follows: C and D are intermeshing gear wheels respectively upon the shaft of the magneto A and the driving shaft B. The gear wheel D is sleeved upon the shaft B so as to be free to revolve thereon, but is 70 connected through the medium of the resilient coupling E to a collar F, fixed upon said shaft. The tension of the spring or coupling E is such that when the engine is 75 in normal operation, power will be transmitted from the shaft B through said spring to the gear wheel D, and from the latter through the intermeshing gear wheel C to the shaft of the magneto, thereby producing 80 the synchronous movement. To produce the 85 non-synchronous movement, a detent is arranged to engage with the wheel D to arrest 90 it from movement during a portion of the engine cycle. As shown, this detent comprises a latch lever G pivotally mounted at 95 H upon a stationary bearing I of the shaft B, while the free end of said latch lever is adapted to engage with a notch or recess J in a flange K on said wheel. This flange K is cammed at a point adjacent the notch J 100 as indicated at L, so that when rotating at normal speed it will throw the latch lever G and prevent it from engaging with the notch. When, however, the speed of rotation is less than normal, the lever G, after 105 passing the cam L, will drop into the notch J, engaging the square shoulder M thereof so as to lock the wheel D from movement.

The temporary arrest of the wheel D is 110 permitted by reason of the resilient coupling

E between said wheel and the collar F, and the continued rotation of the shaft B will place said spring under tension sufficient to gradually accelerate the speed of rotation of the wheel D when released from the latch lever G. The release of said latch is accomplished by a cam N, preferably formed integral with the collar F, and which at a certain point in the cycle, will raise the lever G 10 out of engagement with the shoulder M. This will permit the acceleration of the wheel D under the actuation of the force stored in the spring E, with a result that the speed imparted to the rotor of the magneto 15 is sufficient for the efficient current generation. The mechanism is so timed that the spark occurs during this period of acceleration, thereby utilizing the intensified current. The operation just described will continue as 20 long as the engine is running at a speed less than that of its normal operation. As soon, however, as the normal speed is attained, the interval in which the notch J is in registration with the latch G is not sufficient for the 25 latter to drop into engagement with the shoulder M and consequently the wheel D will be driven synchronously with the shaft B.

To render the action positive and to limit 30 the acceleration of the wheel D, lost motion interlocking engagement is provided between said wheel and the collar F. This, as shown, consists of a sleeve O, preferably integral with the flange K and having jaw 35 members P for engaging with oppositely-extending jaw members Q on the collar F. Between these jaw members sufficient clearance is provided for the independent movement of the collar when the wheel D is 40 locked, but upon the release of the latch G, the lost motion is taken up in the accelerated movement of the wheel D. The inter-engaging jaws prevent the acquired inertia of 45 the accelerated wheel from carrying it beyond a predetermined point, and in this way the relation of the synchronous and non-synchronous movements in the cycle is fixed.

Another feature of my invention is the automatic retarding of the spark when the engine is running at abnormally low speed 50 where the circuit breaker is directly driven from the magneto as indicated at R, Fig. 1. This is accomplished by so timing the mechanism that the sparking occurs during the 55 period of acceleration. Thus when the engine is running at normal speed, the sparking will occur at an advanced point in the cycle, but when the magneto is arrested by engagement of the latch G with the shoulder 60 M, the time of sparking will be delayed and will not occur until after the release of the latch and during the period of acceleration.

Where the circuit breaker is not directly actuated by the magneto, but is operated by 65 some other part of the timed mechanism, the

desired retarding effect may be obtained by a controller operated by the retarded mechanism. As shown in Fig. 3, D' is a gear operating synchronously with the engine, and N' is a cam connected to and directly operated by said gear. G is a latch member controlled by said cam, and K' is the flanged wheel, having the recess J' therein for engaging the latch G. S is a shaft coupled to the wheel K' and having a crank or eccentric S' for operating an igniter push rod S". With this construction the operation of the igniter push rod or circuit breaker is controlled by the flanged wheel K', and consequently when said wheel is arrested by the latch G, the operation of said push rod will be delayed, causing a corresponding delay in the spark.

What I claim as my invention is:

1. The combination with a mechanically-operated electric generator, of a drive mechanism therefor, comprising co-axially arranged drive and driven members having a lost motion coupling therebetween, a resilient member for taking up the lost motion, a notched flange on said driven member, a latch detent for engaging with the notch in said flange to arrest movement thereof during a portion of the cycle, a cam on said drive member for disengaging said latch from said notch, and a cam on said flange for preventing engagement of said latch when said mechanism is revolving at normal speed.

2. The combination with a mechanically-operated electric generator, comprising co-axially arranged drive and driven members having abutting ends, a lost motion coupling between said ends, a resilient member for normally taking up the lost motion, a detent for engaging the driven member to arrest movement of the same during a portion of the cycle, and a cam on said drive member for releasing said detent at a different point in the cycle.

3. The combination with a mechanically-operated electric generator, comprising aligned drive and driven sleeves, a lost motion coupling between said sleeves, a resilient member for normally taking up the lost motion, a detent for engaging the driven sleeve to arrest movement of the same during a portion of the cycle, and a cam on said drive sleeve for releasing said detent at a different point in the cycle.

4. The combination with a mechanically-operated electric generator, comprising a shaft, a driven member loose on said shaft, a drive member fixed to said shaft, the ends of said drive and driven members abutting, a lost motion coupling between said ends, a spring having its opposite ends respectively connected to said drive and driven members, and normally taking up the lost motion, a detent for engaging the driven member

to arrest movement of the same during a portion of the cycle, and a cam on the drive member for releasing said detent at a different point in the cycle.

5. The combination with a mechanically-operated electric generator, comprising a shaft, drive and driven members respectively fixed and loose upon said shaft and having abutting ends, a lost motion coupling between said ends, a spring having its opposite ends respectively connected to said drive and driven members and normally taking up the lost motion, the driven member being provided with a notch, a detent for engaging said notch to arrest movement of the driven member during a portion of the cycle, and a cam on the drive member for releasing said detent at a different point in the cycle.

6. The combination with a mechanically-operated electric generator and a circuit breaker actuating means independent of the generator, of a drive mechanism for said generator, means for retarding said generator and said circuit breaker actuating means to delay the closing period of the latter in the cycle, and for then accelerating the speed to compensate for said delay and to increase the current, and a connection between said circuit breaker actuating means and said driving mechanism for operating said actuating means in synchronism with said generator.

7. The combination with a mechanically-operated electric generator and a circuit breaker, of a driving mechanism for said generator, means operating when said drive mechanism is running at abnormally low speed for alternately retarding and accelerating the speed of said generator during different portions of the same cycle, and a connection between said means and the circuit breaker for driving the latter in timed relation to said operating means.

8. The combination with an electric generator, of co-axially arranged drive and driven members having abutting ends, interengaging jaws formed upon said ends allowing a limited relative rotation between

the members, a spring connecting said members disposed coaxially between the two, said spring normally taking up lost motion, and means for arresting motion of the driven member at a certain point in the cycle and for releasing the same at a different point in the cycle.

9. The combination with an electric generator, and a shaft from which the same is driven, of a drive member, a driven member and a bearing engaged with said shaft, a lost motion coupling between the drive and driven members, a resilient member for normally taking up lost motion between said members, a detent pivotally mounted upon the bearing and extended past the drive member to engage the driven member and arrest its motion at a certain point of the cycle, and a cam upon the drive member intermediately engaging the detent at a different point of the cycle to release the driven member.

10. The combination with an electric generator, of co-axially arranged drive and driven members having abutting ends, a lost motion coupling between said ends, a resilient member for normally taking up the lost motion, and means for arresting the driven member a certain point of its cycle and for releasing it at a different point of the same.

11. The combination with a generator, of a shaft from which the same is driven, a driven member loose upon said shaft, a drive member fixed upon the shaft, the ends of the two members abutting, a lost motion coupling between said ends, a coiled spring connecting the drive and driven members normally taking up lost motion, and means for arresting the driven member at a certain point of the cycle and for releasing the same at another point of the cycle.

In testimony whereof I affix my signature in presence of two witnesses.
